ATTORNEY

UNITED STATES PATENT OFFICE.

CHARLES C. SMITH, OF CLEVELAND, OHIO.

HAMMER.

1,404,150.

Specification of Letters Patent. Patented Jan. 17, 1922.

Application filed March 6, 1920. Serial No. 363,825.

To all whom it may concern:

Be it known that I, CHARLES C. SMITH, a citizen of the United States, residing at Cleveland, in the county of Cuyahoga and 5 State of Ohio, have invented new and useful Improvements in Hammers, of which the following is a specification.

This invention relates to drop forge hammers, and comprehends the provision of a 10 novel construction of means for holding the gibs for the ram associated with the housing in a manner, so that the gibs can be readily and easily moved outwardly or away from each other to permit the ram to be readily 15 separated therefrom as the occasion requires.

In hammers of the above mentioned character, stationary bolts are usually employed to hold the gibs fixed to the housing, and these bolts are frequently broken. In addition to this fact, the piston rod for the ram 20 is sometimes fractured, especially in cold weather, and the general construction of the hammer is such that it necessitates the expenditure of considerable time and labor before the ram can be removed from between 25 the gibs, and the hammer in its entirety properly repaired.

It is therefore the object of this invention to provide means whereby the gibs of the 30 ram are yieldably supported within the housing and normally maintained properly spaced to accommodate the ram, the means for holding the gibs in this position being readily accessible and adjustable to permit 35 the gibs to move within the housing away from each other when it is necessary to remove the rams from between the gibs for any purpose whatever.

The nature and advantages of the invention 40 will be better understood when the following detail description is taken in connection with the accompanying drawings, the invention residing in the construction, combination and arrangement of parts as 45 claimed.

In the drawings forming part of this specification like numerals of reference indicate similar parts in the several views and wherein:—

50 Figure 1 is a view in elevation of a forge drop hammer constructed in accordance with my invention.

Figure 2 is an enlarged vertical sectional view.

55 Figure 3 is a horizontal sectional view taken on the line 3—3 of Fig. 1.

Figure 4 is a similar view, taken on the line 4—4 of Figure 1.

Figure 5 is a perspective view of one of the gibs. 60

Figure 6 is a perspective view of the block and wedge shaped element.

Referring to the drawings in detail, 10 indicates the base of the structure, and from which rises the housing 11 for the gibs 12. 65 It is apparent that there is one of these gibs for each housing, and that the ram 14 is actuated by the piston rod reciprocating between the gibs 12. As shown in Figure 5, each gib is provided with a channel 16 for 70 the reception of the adjacent edge of the ram 14. Each side of the housing is channeled as at 17 to receive the gib 12, the channel 17 being of sufficient dimension as to permit the gib to be moved wholly within the channel 75 in a manner and for a purpose to be hereinafter described.

Each side of the housing is provided with a horizontally arranged pocket 18 opening at one end into the adjacent channel 17, and 80 with a transverse bore 19 opening at the front of the housing and communicating with the pocket 18. A block of steel or other suitable material indicated at 20 is slidably fitted within the pocket 18, one end of this 85 block being perfectly flat to bear against the adjacent side of the gib 12, while the opposite end of the block is bevelled as at 21. Slidably fitted in the transverse bore 19 is an adjustable wedge 22 having a threaded stem 90 23 with which a nut 24 is associated. The wedge shaped side 25 of the wedge 22 bears against the inclined extremity 21 of the block 20 as shown. A washer 26 surrounds the stem 23 and bears against one side of the 95 housing while interposed between the washer 26 and the nut 24 is a coiled spring 27 which functions to exert a pull upon the wedge shaped element 22, thereby causing the latter to force the block 20 against the gib 12 100 holding the latter projected from the housing in an active position.

There is preferably two of these wedge shaped members or blocks used for each gib, and arranged adjacent the opposite ends thereof as clearly 105 illustrated in Figures 1 and 2. Each side of the housing at a point equi-distant between the wedges is formed with an opening 28 to receive one end of a bolt 29 carried by the gib 12. The end of the bolt 29 which is 110 secured to the gib is preferably flared as at 30 and provided with a projection 31 con-

connected with the gib in a manner to prevent rotation or slight turning of the bolt 29. The opposite end of the bolt 29 is provided with a nut 32 which is positioned within the opening 28. Encircling the bolt 29 is a spring 33, the latter having one end bearing against one wall of the opening 28 and its opposite end bearing against the nut 32, this spring being normally under tension to retract the gib within the channel 17 of the housing when the wedges 22 are adjusted to effect a release of the blocks 20 for this purpose.

In practice, should the piston rod 15 become broken, necessitating the removal of the ram 14 from between the gibs 12, as a part of the piston rod often offers considerable trouble and difficulty in the separation from the ram, it is only necessary to slide the wedges 22 within the bores 19 the proper direction to permit the blocks 20 to move outwardly within pockets 18. When the wedge shaped elements 22 are adjusted in this manner, the spring 33 functions to retract the bolt 29, which is connected to the gib 12 and consequently draws the gib wholly within the channel 17 of the housing.

Manifestly, the gibs are separated from the ram 14, thus allowing the latter to be easily removed from engagement for repairs.

While it is believed that from the foregoing description, the nature and advantages of the invention will be readily apparent, I desire to have it understood that I do not limit myself to the details of construction herein shown and described inasmuch as such changes may be resorted to when desired as fall within the scope of what is claimed.

Having thus described my invention what I claim as new is:

In a drop forge hammer, a base, a housing including spaced channelled members supported upon said base, a ram arranged to reciprocate between said gibs, spring influenced wedge shaped members slidably fitted in said housing, blocks slidably fitted in said housing between said wedge shaped members and said gibs, and means for automatically retracting the gibs within the housing to an inactive position when the wedges are adjusted to release said gibs.

In testimony whereof I affix my signature.

CHARLES C. SMITH.
